US00D879428S

(12) **United States Design Patent** (10) **Patent No.:** **US D879,428 S**
Braun et al. (45) **Date of Patent:** **** Mar. 31, 2020**

(54) **SOLE**(71) Applicant: **adidas AG**, Herzogenaurach (DE)(72) Inventors: **Felix Braun**, Nuremberg (DE); **Florian Josel Fick**, Nuremberg (DE); **Pradeepan Indrakumar**, Portland, OR (US); **Yuehong Tu**, Portland, OR (US)(73) Assignee: **adidas AG**, Herzogenaurach (DE)(***) Term: **15 Years**(21) Appl. No.: **29/637,342**(22) Filed: **Feb. 15, 2018**(51) LOC (12) Cl. **02-04**

(57) **CLAIM**

The ornamental design for a sole, as shown and described.

DESCRIPTION

FIG. 1 is a bottom perspective view of a sole showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dot-dash broken lines in the figures and the area(s) within the dot-dash lines show portions of the sole that form no part of the claimed design.

1 Claim, 5 Drawing Sheets# US D879,428 S
